UNITED STATES PATENT OFFICE.

GRACE LOVAT FRASER AND CYNTHIA THIMBELBYE KENT, OF LONDON, ENGLAND.

DESIGN FOR A DOLL.

Application filed September 29, 1927. Serial No. 23,578. Term of patent 7 years.

To all whom it may concern:

Be it known that we, GRACE LOVAT FRASER and CYNTHIA THIMBELBYE KENT, both subjects of His Majesty, the King of England, and residents of London, England, have invented a new, original, and ornamental Design for a Doll, of which the following is a specification, reference being had to the accompanying drawing, forming part thereof.

The figure is a front elevation of a doll, showing our new design.

We claim:

The ornamental design for a doll as shown.

GRACE LOVAT FRASER.
CYNTHIA THIMBELBYE KENT.
